TUMBLING MILL

Nathan Ransohoff, Cincinnati, Ohio, assignor to N. Ransohoff, Incorporated, Hamilton, Ohio, a corporation of Ohio

Application March 1, 1954, Serial No. 413,376

13 Claims. (Cl. 51—164)

This invention is directed to industrial tumbling mills in which batches of workpieces, usually metal parts, are subjected to a surface cleaning and polishing treatment by agitation in the presence of abrasive elements.

In general, such machines comprise a cylindrical compartment or drum mounted for rotation about a horizontal axis; the parts to be treated are confined in the compartment together with a mass of abrasive fragments or particles, sometimes called "stones." During rotation, the commingled mass of stones and metal parts are agitated together in the compartment to enable the stones to clean and polish the surfaces of the metal parts by an abrasive scrubbing action. A machine of this character is disclosed in the patent to Nathan Ransohoff, No. 2,299,032, issued on October 13, 1942.

The invention is disclosed in relation to a tumbling mill of this general class which is constructed to utilize a power driven separator at the discharge end which separates the treated metal parts from the stone as the mass is discharged from the machine. At the charging end, a power loader preferably is utilized to elevate and charge the batches of parts into the charging end of the machine. The power loader and separator enable the machine to treat the parts at a rapid production rate and are of particular advantage in treating relatively small parts.

One of the primary objects of the invention has been to provide a tumbling mill particularly suited for rapidly treating relatively fragile, precision made metal parts which require a cleaning and polishing treatment but which must be carefully protected against the possibility of being nicked or otherwise marred during treatment.

The present machine is intended particularly for the surface treatment of the blades or vanes for the rotors of jet engines, consisting of relatively thin elongated metal plates requiring a smooth surface finish which is free of flaws or nicks. In order to pass inspection after being treated in the tumbling mill, the edges of the vanes must be smooth and free of any measurable nicks or other irregularities. This obviously is a critical problem since the edges of the blades are delicate and are most likely to suffer damage during tumbling.

A certain amount of collision between workpieces is usually associated with the operation of a tumbling mill; however, as a practical matter, this is of no consequence in treating ordinary metal parts because of the shape of the parts. The impacts occur usually as the parts are charged into the machine and as they are discharged from it; during the actual tumbling operation, the parts are suspended in the abrasive mass and thereby protected. In the present machine, means have been provided for gently sliding or skidding the parts along as they are charged into the machine and as they are discharged from it; therefore, at no point during treatment are the parts likely to be damaged by colliding with one another or striking the surfaces of the machine. The machine is therefore adapted particularly for jet blades and other

2

metal parts having thin section or edges which must be protected.

Briefly, the present tumbling mill constitutes a generally cylindrical tumbling chamber having a charging cone at one end for feeding in the parts and a work delivery structure at the opposite end for discharging the work and stone after treatment. During the tumbling operation, the mill is rotated in a given direction for a tumbling period; thereafter the direction is reversed to discharge the parts. The type of abrasive material utilized depends upon the particular requirements of the parts being treated, for example, it may consist of particles of stone, ceramic, Carborundum, or aluminum oxide.

For the purpose of sliding the parts gently during transfer from the charging cone to the tumbling chamber, the charging cone of the present machine has generally convolute related surfaces which, during rotation, provide a ramp action, thereby to elevate the parts and skid them gently into the tumbling chamber without impact. To discharge the parts upon reversal of rotation, the parts are elevated by a spiral chute leading from the periphery of the tumbling chamber to a discharge drum at the discharge end of the chamber. The spiral chute during rotation receives the parts and, again by a sliding action, elevates the parts without collision and deposits them gently in the discharge drum. The drum includes a spiral conveyor which advances the parts and abrasive particles through the drum and deposits them upon an adjacent power separator which separates the parts from the abrasive elements.

Another object of the invention has been to provide, as a component part rotating with the tumbling mill, an apparatus which operates in conjunction with a power separator to return the separated abrasive elements into the tumbling mill for re-use. For returning the abrasive particles, there is provided upon the discharge end of the tumbling mill a concentric collector ring which has a diameter substantially greater than the diameter of the machine. This ring rotates with the machine and its lower portion passes under and intercepts the stream of separated abrasive issuing from the separator. During rotation, the abrasive particles are elevated and discharged back to the machine by a series of radial chutes attached to the rear wall of the ring and rotating with it. The abrasive is charged into the outer ends of the chutes as they rotate through the mass in the lower portion of the ring; the abrasive flows by gravity during continued rotation.

A further object of the invention has been to provide a power loader at the charging end of the mill which elevates the parts and slides them gently into the open end of the charging cone in a positive manner without subjecting the parts to impacts. The power loader includes a vertically movable hopper which projects toward the cone, the hopper being arranged to remain in a horizontal plane during its elevating motion and to pivot to an inclined, discharge position at its upper level of travel. In its horizontal position, the hopper moves vertically in a plane spaced from the end of the cone for clearance. Upon pivoting to its inclined position, the end of the hopper projects into the cone so as to guide the parts in a positive manner into the cone. Prior to being lowered, the hopper first pivots back to its level position, thus retracting the projecting end back to its former plane for downward movement clear of the end of the cone.

Various other advantages of the invention will be more fully apparent from the following detailed description taken in conjunction with the drawings.

In the drawings:

Figure 19 is an enlarged side view showing a modified tumbling mill in which the stones are separated in the discharge cone as distinguished from the power separator illustrated in Figure 1.

General arrangement and operation

Referring to Figure 1, which illustrates the tumbling mill 10 installed for production operation, the parts to be treated are fed into the machine by the power loader indicated generally at 11. The loader elevates batches of parts and slides them into the open charging end of the mill. The tumbling mill is rotated in a given direction during the tumbling operation; thereafter it is rotated in the reverse direction for discharging the finished parts to a power separator indicated generally at 12. At this point, the treated parts, together with the stones or other abrasive elements, are discharged upon the separator which returns the stones back to the mill for re-use and concurrently advances the finished parts to a discharge point.

The tumbling mill comprises a series of component cylindrical sections in end to end relationship, the sections being welded or otherwise joined together for rotation as a unit. Each section is slightly conical to provide

a sloping surface which causes the material to gravitate in the desired direction during rotation of the mill. Upon operation of the power loader, with the machine rotating in tumbling direction, the parts are charged into the loading cone indicated at 13 and are advanced from the cone to the tumbling chamber 14 by a scoop structure within the cone. A mass of commingled parts and stones as indicated at 15 in Figure 2 is maintained within the tumbling chamber during the tumbling treatment.

10 Joined to the opposite end of the tumbling chamber is a collector chamber 16 which includes a work discharge drum 17 (Figure 2) for conveying the work and stones from the tumbling chamber to the separator upon reversal of rotation to discharge direction. During rotation in discharge direction, the separated stones are fed back from the separator to the collector chamber which serves as accumulator for the used stones. After all of the parts and stones are conveyed from the tumbling chamber and separated, the mill is again rotated in the tumbling direction. The stones which have been accumulated in the collector chamber are now fed back into the tumbling chamber and, at the same time, a fresh batch of parts is introduced into the tumbling chamber by way of the charging cone 13.

25 As indicated in Figure 1, the tumbling mill is rotatably supported by rings 18-18 which are tracked upon flanged rollers 20 mounted for rotation at opposite sides of the mill. The driving system by which the mill is rotated is well known in the art. In the present disclosure it comprises an electric motor and speed reduction unit 21, the motor being mounted upon a frame 19. A sprocket chain 22, which meshes with a sprocket ring 23 (Figure 2) on the tumbling mill, completes the driving connection with a sprocket of the speed reduction unit.

30 As the work is charged into the cone, the tumbling mill is rotated in tumbling direction as indicated by the arrows in Figures 3 and 8. Upon being introduced into the cone, the parts slide down the sloping wall of the cone toward the pickup opening 24 (Figure 3) of the scoop which is indicated generally at 25. The scoop elevates the parts and advances them through the opening 26 (Figure 2) in the forward membrane or head 27 of the tumbling chamber.

35 Upon completion of the tumbling treatment and reversal of rotation to discharge direction, the parts and stones pass through the opening 28 in the rearward membrane or head 30 of the tumbling chamber (Figure 11). This opening communicates with a spiral ramp or chute 31, the chute having its opposite end communicating with the work discharge drum 17 as shown in Figures 7 and 8. The discharge drum is provided with a spiral vane 32 which advances the parts and stones through the tube to the separator 12 as described in detail later.

40 For the purpose of recovering and conveying the stones back to the tumbling chamber, the forward end of the collector chamber 16 includes a stone collector ring 33, the separator 12 being provided with a trough 34 having an end projecting above the ring 33. As best shown in Figure 12, the ring includes a series of radial stone return chutes 35 which pick up the abrasive particles from the lower portion of the ring during rotation of the mill in either direction. During rotation, the chutes advance the material through openings 36 formed in the wall 37 of the ring and into the collector chamber 16.

45 After passing into the collector chamber, which is slightly conical for this purpose, the stones advance back toward the head 30 of the tumbling chamber where they are picked up by a second series of radial stone return chutes 38. These chutes pick up the stones and deliver them through the openings 40 into the tumbling chamber for re-use, but only when the mill is rotating in tumbling direction.

50 Briefly therefore, the commingled mass of abrasive and parts is agitated in the tumbling chamber during rotation in the tumbling direction, and is discharged upon the

separator during reverse rotation. At this point the treated parts are separated from the stones which currently are fed back into the collector chamber where they advance back to the tumbling chamber when the direction of rotation is again reversed to tumbling. During both the charging and discharging operations, the parts are advanced under carefully controlled sliding motions to protect the parts from impacts which lead to damage.

Charging cone

As noted earlier, the parts to be treated are charged into the loading cone 13 by the hopper of the power loader 11, which moves vertically and pivots to the position shown in broken lines in Figure 1 to elevate and transfer the parts to the cone. As best shown in Figures 2 to 6, the open end of the cone is delineated by a lip 41 to prevent any of the parts from dropping from the cone after they are loaded into it. As the cone rotates in tumbling direction, the parts gravitate down the sloping surface of the cone until they contact the flow plate 42 which controls the flow of workpieces to the charging scoop 25. The flow plate includes the opening 24 for passage of the work parts into the charging scoop, the parts being elevated and gradually advanced by the scoop through the opening 26 of membrane 27 into the tumbling chamber.

The flow plate and scoop are fabricated from sheet metal suitably configured to fit within the cone, the parts being attached preferably by welding as indicated later. As best shown in Figures 5 and 6 the flow plate includes a flat portion 43 which is located at right angles to the axis of rotation in a plane spaced outwardly a substantial distance from membrane 27. As viewed in tumbling direction, the flat portion 43 forms the leading end of the flow plate; a sloping portion 44, approximately half the area of the plate, forms the trailing portion. The sloping surface 44, combined with the sloping surface of the cone, guides the parts in a smooth sliding path toward the opening 24 leading to the scoop.

Opening 24 is formed in an area overlying both the leading and trailing edges of the flow plate; hence the leading or pickup edge of the opening, as indicated at 45, is disposed outwardly a substantial distance from the trailing edge 46. During rotation in tumbling direction, as indicated by the arrow, the parts collect in the lower portion of the cone in contact with the flat wall portion 43, then follow the sloping surface 44 as the opening rotates in its orbit below the axis of rotation. As the leading edge 45 passes through the mass of parts and begins to move upwardly in its orbit, the parts are trapped in the scoop 25.

As best shown in Figure 4 in its upper position, the leading portion 47 of the scoop slopes downwardly from the flow plate toward the lower edge of the opening 26 leading to the tumbling chamber. As the leading edge 45 passes through the mass of parts, the portion 47 assumes an angle generally the reverse of that shown in Figure 4; upon passing the axis of rotation, the plane of the scoop surface becomes generally parallel to the axis of rotation. Thereafter, as the portion 47 continues to rotate upwardly with the parts trapped in it the angle of its surface progressively changes to that shown in Figure 4, causing the parts to slide downwardly through the opening as indicated by the arrows (Figure 4). The parts are thus skidded through the opening as soon as the pitch of scoop portion 47 becomes sufficiently great; this occurs at some point during rotation above the axis, usually before the portion 47 reaches the maximum slope shown in Figure 4.

As best shown in Figure 6, the scoop 25 is generally convolute and its leading end 48, which is welded to the cone, is generally parallel to the axis of rotation. From the leading end, the scoop curves from the periphery of the cone upwardly toward the axis of rotation. Thus upon being trapped in the leading portion of the rotating

scoop, the parts begin their elevating motion toward opening 26.

The inner edge of the scoop, as indicated at 50 in Figure 5, lies flush against the surface of membrane 27 to which it is welded. As shown in Figure 6, the scoop partially surrounds opening 26. The outer edge of the scoop, as indicated at 51, corresponds to the contour of the flow plate to which it is welded. As best shown in Figure 6, the trailing portion 49 of the scoop is generally flat and is disposed in a sloping plane substantially corresponding to the slope 47 shown in Figure 4. The trailing end 52 of this portion contacts the surface of the cone at an angle to the axis of rotation (due to the slope of the trailing portion 49) and is welded to the cone as indicated.

Referring to Figure 2, the flow plate and scoop are shown in a position corresponding to the section taken along line 5-5 of Figure 3 but with trailing portion 49 in elevation. From this view, it will be seen that the parts will also flow inwardly across the end 52 of the scoop, as indicated by the arrow, upon rotation in the discharge direction. In other words, the trailing end, which then becomes the leading end of the scoop, will also advance parts along the sloping portion 47 of the scoop toward the opening 26. The scoop provides more efficient collection and advancement of the parts during rotation in the tumbling direction; however, during discharge rotation, the scoop is effective to return any parts to the tumbling chamber which may happen to fall through opening 26 during tumbling treatment or discharge. It will be seen therefore that the scoop provides ramp surfaces which are effective to slide the parts smoothly into the tumbling chamber during rotation in either direction.

Work discharge

After a timed tumbling period, the direction of rotation is reversed in order to advance the mass of treated work and abrasive from the tumbling chamber 14 to the discharge drum 17. As the tumbling chamber rotates, the mass of work and abrasive is in contact with the rearward head or membrane 30, which includes the opening 28 leading to the receiving end of the spiral chute 31 previously mentioned. This chute resides adjacent the opposite side of membrane 30 and its upper or discharge end communicates with the end portion of the work discharge drum 17, as best shown in Figure 8.

Referring to Figure 2, it will be observed that a portion of the spiral chute is offset inwardly from the plane of membrane 30 to provide space for the radial stone return chutes 33 which extend from the periphery of the collector drum to the central stone return opening 40, previously mentioned. As best shown in Figure 2, the chutes 33 project through the end portion of the work discharge drum 17 but there is no communication between the chutes and the portion of the drum through which they project.

As viewed in Figure 8, the receiving opening 28 extends upwardly from the periphery of the tumbling chamber and is sufficiently large to permit passage of the parts into the spiral chute during rotation in the tumbling direction. The chute is generally square in cross section as delineated by opening 28, and includes an inclined end wall 53 which connects the end of the chute to the opening. The chute section at the opening is in the form of a box 54, consisting of side walls 55-55 and a back wall 56, the edges of the side walls being welded directly to the surface of head 30 around the edges of opening 28. The box section and chute proper blend together and spiral away from the surface of head 30 (Figure 8). Interposed between the box 54 and chute 31 is connecting chute 57 which inclines away from the plane of membrane 30 to provide space for the stone return chutes as noted above. The inclined connecting chute 57 and spiral chute 31, being spaced from the membrane 30, are provided with a forward wall 58 (Figure 7).

The discharge end of the spiral chute blends into an

opening 60 communicating with the discharge drum as best shown in Figure 8. As the tumbling chamber rotates in the discharge direction, the parts together with the abrasive particles, enter the receiving opening 28 and pass into the spiral chute where they are elevated toward the opening 60 of the discharge drum. In other words, the spiral chute defines a ramp having a gradual slope, such that the parts which are caught in the rotating chute are elevated to the discharge drum by a sliding motion. Upon reaching the discharge cone, the parts slide from the 10 surface of the chute to the interior of a cone 61 without any abrupt change in their direction of motion. Cone 61 forms a part of drum 17 but its slope is reversed and considerably steeper. For assembly purposes, the two cones are flanged as at 62 and are attached together by 15 bolts 63 passing through the flanges.

Referring to Figures 7 and 8, it will be noted that the surface of the spiral chute blends smoothly with the internal surface of cone 61 such that the parts slide smoothly from the surface of the spiral tube to the cone 20 as the delivery end of the chute passes below the axis of rotation in its orbit. Upon being deposited in the cone 61, the parts slide forwardly toward the end of discharge drum 17 because of the slope of the cone. Within the work discharge cone is a spiral conveyor vane 32 for conveying the parts toward the discharge end of the drum.

During treatment in the tumbling chamber, the parts are suspended in the abrasive mass and suffer no damage; however their surfaces must be protected from being nicked or otherwise damaged during discharge since parts are no longer suspended in the mass. In the conventional tumbling mill, there is a natural tendency for some of the treated parts to drop from the retrieving scoop or other member during rotation, such parts usually falling back into the tumbling chamber. Ordinarily this presents no special problem since the shape of the parts allows them to absorb such impacts without damage.

As explained earlier, the present machine is intended particularly for handling delicate parts such as rotor vanes for jet engines and similar parts which are rejected even if slightly nicked or scratched. The spiral chute 31 and its cooperating feed cone 61 provide gentle but positive advancement of the parts from the tumbling chamber to the discharge drum. When rotation progresses to the point where the work parts enter the cone opening 60, the parts slide smoothly into the cone and axially away from the opening, as indicated by the arrow in Figure 7. Accordingly, as rotation continues, the work parts have no opportunity to hang up at or near the delivery end of the chute and to drop back down the chute towards the receiving opening as rotation continues. Otherwise expressed, the cone 61 forms a trap to convey the parts down its slope and away from opening 60 as soon as the parts enter the cone. In actual practice, it is found that none of the parts escape after they enter the spiral chute; instead they are skidded along the ramp surfaces of the chute and cone and have no opportunity to drop out at any point during rotation.

Upon sliding down cone 61, the parts and abrasive fragments are caught in the leading end of spiral conveyor vane 32 and advanced toward the separator 12 as noted earlier. It will be noted in Figure 2, that the vane 32 is relatively high at the rearward end of drum 17 and that the vane decreases progressively in height toward the delivery end. The lead of the vane increases progressively towards the delivery end of the drum such that the parts advance at an increasing rate of speed. Accordingly, the mass of parts and abrasive fragments, which accumulates at the inner end of the cone, is delivered in a continuous stream to the separator 12 where the parts and abrading elements are separated from one another.

Separator

The separator shown in Figure 1 is a commercial product and its exact structure is not essential to the present

invention. However, since it cooperates directly with stone return apparatus, a general understanding of its structure and operation is considered necessary to a complete understanding of the invention. As the mixture of workpieces and stones drop from the delivery end of drum 17, the stream falls by gravity upon the receiving trough 65 of the separator. In order to advance the parts, the trough is inclined downwardly and is also vibrated by an electric vibrator or the like (not shown).

As the stream of parts and stone fragments approach the end of trough 65, the metal parts are attracted to pulley 67 which is magnetized. A moving conveyor belt 66 is trained over the pulleys 67 and 68. The parts which are attracted to pulley 67 contact the conveyor belt and are thus elevated and conveyed upon the belt. The pulleys are rotatably mounted upon the frame 70 of the separator. Rotary motion is imparted to pulley 67 by an electric motor 71 connected to the pulley by a sprocket chain drive 72.

The conveyor belt is advanced at a rate of speed consistent with the rate of discharge of the tumbling mill and the parts are conveyed upon the upper run of the belt in the direction indicated by the arrow. As the parts reach the delivery end of the conveyor belt, they 25 drop from it by gravity since pulley 68 is not magnetic. From this point, the parts are conveyed from the machine in finished condition.

The stones or other abrasive particles, which are of nonmagnetic material, continue advancing down the 30 vibrating trough 65 and are discharged upon the stone return trough 34 previously noted. This trough is inclined downwardly in reverse to trough 65 and its lower or discharge end 73 projects partially into the lower portion of the collector ring 33. This trough is likewise 35 vibrated by an electric vibrator or other means to facilitate the advancement of the stones. Upon reaching the collector ring, the stones are advanced back to the tumbling chamber by the radial stone return chutes, as explained in detail later.

According to the present disclosure, the separator is 40 utilized to serve several tumbling mills, the separator being provided with flanged wheels 74 which ride upon the tracks 75 extending transversely across the discharge ends of several tumbling machines. The separator may 45 be provided with an electric motor 76 connected by a sprocket chain drive 77 to the wheels for propelling the separator relative to the tumbling machines.

In order to prevent interference between the ends of 50 the troughs 34 and 65 and the parts of the tumbling mill which they interfit, the troughs are pivotally mounted upon the separator frame. The troughs thus may be 55 swung to positions which clear the projecting ends of the discharge drum and the stone collector ring when the separator is shifted from one tumbling mill to another.

In the event that the nature of the work requires the 60 use of stars, slugs, or the like, fabricated from a magnetic material, or if the workpieces are not magnetic, then a separator utilizing a different principle of operation is utilized. By way of example, a screen type separator 65 may be utilized which has a mesh suitable to separate the abrasive particles from the relatively larger work parts. In this instance a return trough similar to trough 35 preferably is utilized to return the abrasive particles to the collector ring 33.

Stone return

The collector ring 33 is considerably larger in diameter than the collector chamber and is mounted upon the end of the collector chamber by a series of bolts 78 (Figure 2) passing through a flange 80 into the end wall 37 of the ring. The annular wall 81 of the ring, which accumulates the returning stones, is generally conical and is joined by a cylindrical wall 82 which joins end wall 37. The forward edge of the conical wall includes 75 a lip 83 which confines the returning stones as they

gravitate toward the end wall during rotation of the ring. The returning stones are elevated from the lower portion of the ring by the radial chutes 35 previously noted.

Described with reference to Figures 12 to 14, there is provided a set of six stone return chutes 35, the chutes being mounted radially upon the end wall 37. Each chute comprises a pair of spaced side walls 84-84, joined by a front wall 85. The end wall 37 of the ring forms the fourth wall of the chutes; the side edges of the side walls being joined to the wall by welding as at 86. The outer end portions of the side walls 85 terminate in spaced relationship to the periphery of the cylindrical wall 82 (Figure 12) to provide the stone receiving openings 87-87 at opposite sides. The inner ends of the chutes communicate with the openings 36 of wall 37, each chute having an inclined end wall 88 which directs the stones through the openings to the interior of the collector chamber.

As shown in Figures 12 and 13, each chute is provided with a baffle 90 which extends parallel with the side walls 84 in a plane intermediate the two side walls. The outer end of the baffle joins the surface of the ring and the inner end of each baffle terminates short of the inner end of the chute. During rotation of the ring, a portion of the stones in its lower portion are deflected by the endwise portion of the baffle through the openings 87 into the chute. As the chute assumes an inclined position during rotation, the stones slide by gravity down the chute into the collector chamber where they collect in the lower portion to be elevated by the second set of return chutes 38 to the tumbling chamber.

It is to be noted that the baffles 90 cause the stone return chutes to collect and return the stones during rotation of the machine in tumbling or discharge direction. In other words, in either direction of rotation, the stones enter one or the other of the openings 87 and are guided into the chute by the baffles.

In order to prevent any of the stone fragments from bouncing from the collector ring, there is provided a deflector disk or baffle 91 in the plane of the lip 83. The disk is attached to the end of the discharge drum and delineates an annular space to accommodate the end of trough 34 which projects into the ring.

As best shown in Figures 7 to 11, the stone return chutes 38, leading from the collector chamber to the tumbling chambers are generally similar to the chutes 35 except that a set of three is utilized. The chutes 38 are arranged to return the stones only during rotation in the tumbling direction and to idle during rotation in the discharge direction. After all of the workpieces and stones have been discharged and the machine is reversed to tumbling direction, the mass of stones which has accumulated in the collector chamber is fed back into the tumbling chamber.

Referring to Figure 8, each chute 38 comprises a pair of side wall 92-92 welded upon the surface of membrane 30 and enclosed by a cover plate 93. The side wall 92, which is at the leading side of the chute during rotation in tumbling direction, has its outer end spaced from the periphery of the collector chamber to provide the opening 94. The opposite side wall extends outwardly to the periphery of the chamber, the arrangement thus providing a single entry chute. Therefore, during rotation in the tumbling direction, the stones enter the openings 94 as indicated by the arrow in Figure 8, and during rotation in the opposite direction the chutes pass through the mass without trapping any stones.

As explained earlier, the inner end portions of the chutes 38 pass through the wall of cone 61 but are not in communication with it. An end wall 95 is mounted within the cone at the plane of the chutes to close off this area. The inner ends of the radial chutes adjoin one another at the central axis of the machine and the end of each chute is provided with an inclined end wall 96

which is generally V-shaped as viewed in Figures 9 and 10. The forward edges 97 of the end walls all radiate from the axis of the chamber and interfit to form a spider, as viewed in Figure 11, subdividing the discharge opening 40 of head 30. The inclined end walls 96 direct the stones through the opening into the tumbling chamber and prevent stones from tumbling back through an adjacent chute during rotation.

Power loader

The power loader (Figures 15 to 18) in general comprises a base structure 98 supporting a vertical frame 100 which has a vertically movable hopper 101 tracked for vertical movement within it. The hopper is connected by a cable 102 to a standard power hoist 103 mounted at the top of the frame. The forward end of the hopper is in the form of a discharge chute 104, the outer end of which is normally spaced away from the end of the charging cone (Figure 1). Upon reaching its elevated position, as indicated in broken lines in Figure 15, the hopper, which is now adjacent the open end of the charging cone, swings about a pivot point to an inclined discharge position. This motion projects the end of the chute within the open end of the cone, as indicated, causing the parts within it to be fed into the cone.

In order to feed the parts, the hopper is provided with a false bottom 105 (Figure 17) which is vibrated by a power operated vibrator 106 connected to it. The vibration, combined with the inclination of the false bottom, causes the parts to slide down the slightly inclined surface upon which they are resting. The vibrator may be powered electrically or otherwise and is not disclosed in detail since it is a standard commercial unit.

Described in detail, the frame 100 comprises a pair of vertical channel members 107-107 fabricated from structural steel and having a cross beam 108 extending across the top of the frame. The ends of the beam which are joined to the upper ends of the channels are braced by the gusset members indicated at 110. The hoist unit 103 is attached to the beam by suitable hangers indicated at 111. The several structural members are attached together preferably by welding.

The hopper is pivotally mounted upon a vertically movable carriage 112, having sets of rollers 113 which are tracked at opposite sides between the flanges of the channels 107. The rollers are rotatably journaled upon axles 114 which are attached to the side members 115-115 of the carriage. The carriage is U-shaped, the side members having their lower ends joined by a cross beam 116 (Figure 16). The lower portion of the carriage is provided with a pair of forwardly projecting brackets 117-117, one for each side member, the brackets located immediately above beam 116; the hopper is also provided with downwardly projected brackets 118-118. The respective pairs of brackets are pivotally connected together at their outer ends by the pivot shaft 120.

The hopper is formed of sheet metal and is preferably of welded construction. It includes a pair of spaced side walls 121-121 which, as viewed from the side, have an upwardly inclined lower edge, joined by a curved bottom plate 122 which forms the discharge chute. The false bottom 105 is similarly curved and nests within the inclined bottom plate in slightly spaced relationship (Figure 17). To prevent particles of material from falling into the space beneath the false bottom, its upper edges are protected along opposite sides by the angular flanges 123-123 which are welded to the interior surface of the side walls 121. The flanges overhang the upper edge portions of the false bottom, clearance being provided between the two surfaces to allow the vibratory motion. The rearward end of the hopper may be provided with a door 124 which is hingedly connected as at 125 to a panel 126 enclosing the lower portion of the hopper. The door includes latches 127 for locking it in closed position.

As shown in Figure 16, the cable 102 is connected at

11

its lower end to a cross bar or single tree 128 which applies equal cable pull upon the opposite sides of the hopper as it is elevated and tilted. The cable is anchored at the center of the bar as at 129 and a pair of equalizing cables 130—130 is anchored upon the opposite end portions of the bar as at 131. The lower ends of the equalizing cables are anchored as at 132 upon the projecting opposite ends of a cross bar 133 which extends across the bottom of the hopper, the bar preferably being welded to the bottom of the hopper. The equalizing cables are normally confined in the curved cable guides 134—134 which are welded upon the side plates at opposite sides of the hopper (Figure 18).

The hoist unit includes the usual reduction gearing in driving connection with a cable drum, and upon being energized, elevates the hopper to the position shown in broken lines. By reason of the shape of the hopper and its relationship with the carriage and cable, the major weight load is carried in the rearward portion of the hopper in cantilever fashion relative to frame 100. Because of the load distribution, the hopper tends to rotate toward the left, as viewed in Figure 15, as its rearward end is hoisted free of the base 98 upon which it normally rests. However, the forward portion of the hopper is provided with a pair of guide pins 135, confined for vertical movement in a pair of vertical guide channels 136 attached to the channels 107. As the cable begins to elevate the hopper, the hopper tends to rotate about its pivot shaft 120; however, this motion is restrained by the guide pins 135, causing the hopper to remain in its horizontal portion as it is elevated.

The hopper remains in its horizontal position as the end of the chute passes the end of the loading cone. Upon reaching the discharge elevation, the upper rollers 113 engage a pair of stops 137—137 which are attached to the channels on opposite sides. At this point, the carriage is stopped while the hoist continues elevating the hopper. This causes the hopper to pivot relative to the carriage about the pivot shaft 120 until it reaches the inclined discharge position shown in broken lines. It will be noted that the relationship of the pivot point to the plane of the hopper causes the forward end of the chute to move forwardly and to project into the open end of the charging cone as it tilts. When the hopper reaches this position, the vibrator 106 is energized to facilitate the discharge of parts. Thereafter, the hoist is energized in the reverse direction, causing the hopper first to assume its horizontal position and then to descend with the carriage to its loading position.

It will be noted that the cable guides 134 provide a rolling action with respect to the equalizing cables 130 as the hopper swings to and from tilted position. The cable guides reduce the cable tension incident to the tilting operation, since the guides increase the cable angle at the elevated position, as indicated by the broken lines 102a in Figure 15. In the absence of the guides, the point of application of the tension would swing in an arc about pivot shaft 120 and approach a dead center relationship as the hopper tilts.

The guide channels 136 referred to above, are in the form of angle irons which are attached preferably by welding to the side webs of the channels 107, such that the pin 135 is confined between the flange of channel and the flange of the angle iron. The upper ends of the angle irons are joined by generally horizontal guide flanges 138 at opposite sides. The forward end of each horizontal guide flange includes an outer portion which slants downwardly as at 140. The adjoining end portions of the vertical and horizontal guide structures are reinforced by the gusset plates 141 at opposite sides, which are welded to the channels 107 and to the angle iron structures. It will be noted that the flanges of the vertical and horizontal guides are connected together by a curved flange indicated at 142.

As the hopper is elevated to the stops 137, and while

12

still in horizontal position, the guide pins reach a position above the upper ends of the guides as indicated at 135a in broken lines. As the hopper rotates about the pivot shaft 120 toward its inclined position, the pins swing in an arc about the pivotal axis to the second position shown in broken lines at 135b. Upon reaching position 135b the pin engages the inclined flange 140 of the guide, which thus provides a stop limiting the angular position of the hopper. Upon reversal of the hoist motor, the hopper swings back to level position as explained above, thereby causing the guide pins 135 to return to the plane of the vertical guide channels 136 and to reenter the guides as the hopper descends. The guide pin and guide channel structure is thus effective to maintain the hopper in its horizontal position in a positive manner until it reaches its upper or lower limit of travel. This prevents interference with the end of the cone and possible damage to the equipment.

The loader preferably is provided with an automatic control system for regulating in sequence the operation of the hoist motor and vibrator. The control system follows conventional engineering practice and is not disclosed in the drawings.

Modified structure

The tumbling mill disclosed in Figure 19 is similar to the structure above described except that the collector ring 33 has been omitted and instead, the abrasive fragments, such as stones, are separated in the discharge drum 17 and fed by gravity directly back to the collector chamber 16. The drum is perforated as at 143 to allow the stones to be screened out, as indicated by the arrows, as the stream of workpieces and stone is advanced through the drum by the spiral conveyor 32. As the stones drop into the collector drum, they gravitate toward the membrane 30 of the tumbling mill, there to be picked up by the radial stone return chutes 38. This structure includes the spiral chute 31 and related structure, as previously described for elevating the parts and stones from the tumbling chamber to the discharge drum.

In the modified structure, a spray pipe 144 projects inwardly into the open end of the drum, the pipe being supported by exterior mounting means (not shown). The pipe is connected to a source of water pressure or treating liquid, and includes perforations suitable to direct jet streams of liquid upon the advancing parts and abrasive fragments. The liquid treatment is desirable in treating certain classes of work and it is found to facilitate the discharge of the parts and to dislodge any particles adhering upon their surfaces.

After passing through the abrasive fragments and workpieces, the liquid drains into the collector chamber. For draining the liquid from the collector chamber, the wall of the chamber is provided with one or a series of screened openings as indicated at 145, the screen 146 being of a mesh to restrain the abrasive particles. Since the work parts and stones are not discharged to the external separator, the end of the collector chamber is closed off by the end wall 147.

The modified machine operates upon the principles described earlier, except that the collector ring is omitted and the power separator is not utilized. However, the modified machine is intended to be charged by the power loader in the manner described earlier. The modified structure provides the same advantages of treating fragile workpieces at a rapid production rate and of protecting the parts from being nicked or otherwise damaged during passage through the machine.

Having described my invention I claim:

1. In a tumbling mill having a generally cylindrical tumbling chamber rotatable about its longitudinal axis and including forward and rearward end walls, the forward end wall including a central charging opening and the rearward end wall including a discharge drum projecting outwardly therefrom and having a discharge open-

ing at the periphery of the tumbling chamber; means for charging and discharging workpieces by a sliding action to and from the tumbling chamber comprising, a charging cone mounted upon the forward end wall concentric to the charging opening thereof, the cone having an open outer end, the cone tapering outwardly from said open end toward the forward end wall, a vertical loader frame disposed adjacent the open end of the cone, said frame having a work charging hopper including a discharge end projected toward the open end of the cone and normally disposed below the cone, guide means connecting the hopper to the frame for vertical movement of the hopper in a fixed path spaced outwardly from the open outer end of the charging cone, pivot means connecting the hopper to the guide means, the pivot means located below the discharge end of the hopper, hoist means mounted on the frame and connected to the hopper at a plane rearwardly from the pivot means, thereby to elevate the hopper to a position adjacent the opening of the cone and to swing the discharge end thereof downwardly in an arc into the opening of the cone for sliding the workpieces into the cone, charging means in the cone including a scoop having opposite ends joined to the periphery of the cone and having a curved portion partially surrounding the central charging opening, said curved portion disposed at an angle to the axis of rotation, said scoop elevating the workpieces by a sliding action from the cone to said charging opening by rotation of the cone, and a spiral chute mounted externally upon said rearward wall and having an intake end in communication with the said discharge opening, said spiral chute having a delivery end communicating with the discharge drum, thereby to elevate the workpieces to the drum by sliding action during rotation of the tumbling chamber.

2. In a tumbling machine having a generally cylindrical tumbling chamber rotatable about its longitudinal axis, the chamber including forward and rearward end walls, the forward end wall including a central charging opening; means for charging workpieces by a sliding action through said charging opening comprising, a charging cone having an end mounted on said forward end wall concentric to the charging opening, the cone having an open outer end, the surface of the cone tapering outwardly from its open end toward the end wall, a flow plate mounted in the charging cone and having a portion disposed in a plane generally parallel to the end wall and spaced outwardly therefrom, the flow plate having a second portion which slopes inwardly toward the said end wall, the flow plate having an opening in the marginal portion thereof, said opening rising from the periphery of the charging cone, said opening delineating a leading edge in the parallel portion of the flow plate and a trailing edge in the sloping portion thereof, the taper of the cone and sloping portion of the flow plate guiding the workpieces in sliding motion toward and through the flow plate opening during rotation of the machine, and a charging scoop mounted between the flow plate and said end wall, the charging scoop having a leading edge joining the periphery of the cone, the scoop having a leading portion joining said leading edge which is generally convolute, the scoop having an outer edge joined to the flow plate around the edges of the flow plate opening, the scoop having an inner edge joined to the end wall of the tumbling chamber around the edge of the charging opening, the scoop having a trailing end joined to the periphery of the cone, the axis of the convolute portion being oblique to the axis of rotation and providing a guide surface extending angularly to the axis of rotation from the opening of the flow plate to the central charging opening of the end wall, the leading edge of the scoop, during advancement of the convolute portion below the axis of rotation, passing under the workpieces advanced through the flow plate opening, the convolute portion elevating and advancing the workpieces by a sliding action toward and

through the charging opening into the tumbling chamber during advancement thereof above the axis of rotation.

3. In a tumbling machine having a generally cylindrical tumbling chamber rotatable about its longitudinal axis, the chamber including forward and rearward end walls, the forward end wall including a central charging opening; means for charging workpieces by a sliding motion through said charging opening comprising, a charging cone having an end mounted on said forward end wall concentric to the charging opening, the cone having an open outer end, the surface of the cone tapering outwardly from its open end toward the end wall, a flow plate mounted in the charging cone and having a portion disposed in a plane generally parallel to the end wall and spaced outwardly therefrom, the flow plate having a second portion which slopes inwardly toward the said end wall, the flow plate having an opening in the marginal portion thereof, said opening rising from the periphery of the charging cone, said opening delineating a leading edge in the parallel portion of the flow plate and a trailing edge in the sloping portion thereof, the taper of the cone and sloping portion of the flow plate guiding the workpieces in sliding motion toward and through the flow plate opening during rotation of the machine, and a charging scoop mounted between the flow plate and said end wall the scoop extending from the opening of the flow plate to the central charging opening of the end wall of the tumbling chamber, the scoop having a leading edge joining the periphery of the cone adjacent the leading edge of the flow plate opening, the scoop being generally convolute and having a trailing end joined to the periphery of the cone adjacent the trailing edge of the flow plate opening, the axis of the convolute scoop being oblique to the axis of rotation of the machine, whereby workpieces entering the flow plate opening are elevated and advanced by the scoop in sliding motion toward and through the charging opening during rotation of the machine.

4. In a tumbling machine having a generally cylindrical tumbling chamber rotatable about its longitudinal axis, the chamber including forward and rearward end walls, the forward end wall including a central charging opening; means for charging workpieces by a sliding motion through said charging opening comprising, a charging cone having an end mounted on said forward end wall concentric to the charging opening, the cone having an open outer end, the surface of the cone tapering outwardly from the said outer end toward the end wall, a flow plate mounted in the charging cone and having a portion disposed in a plane generally parallel to the end wall and spaced outwardly therefrom, the flow plate having a second portion which slopes inwardly toward the said end wall, the flow plate having an opening in the marginal portion thereof, said opening rising from the periphery of the charging cone, said opening delineating a leading edge in the parallel portion of the flow plate and a trailing edge in the sloping portion thereof, the taper of the cone and sloping portion of the flow plate guiding the workpieces in sliding motion toward and through the flow plate opening during rotation of the machine, and a charging scoop plate mounted between the flow plate and end wall, the scoop plate having respective leading and trailing edges joining the periphery of the cone adjacent the leading and trailing edges of the flow plate opening, the scoop being generally convolute and having an inner edge joining the end plate and partially surrounding the charging opening thereof, the scoop having an outer edge joining the flow plate and surrounding the flow plate opening, the leading or trailing edges of the scoop advancing under the workpieces passing through the flow plate opening depending upon the direction of rotation of the machine, whereby the scoop is effective to advance the workpieces by a sliding action through the charging opening during rotation in either direction.

5. In a tumbling machine having a tumbling chamber mounted for rotation about its longitudinal axis in charg-

15

ing and discharge directions and having a rearward end wall including a coaxial discharge drum projecting outwardly therefrom, means for discharging material from the tumbling to the discharge drum by a sliding action comprising, a spiral chute mounted externally upon said rearward end wall, the spiral chute being generally square in cross section in the form of a tube with the spiral convolution residing generally in the plane of the end wall, the end wall having an intake opening at the periphery of the tumbling chamber to receive the material in the chamber, a cone mounted externally of the end wall coaxial to the discharge drum, and having an end connected to the discharge drum, said cone tapering outwardly from the end wall toward the discharge drum, the said spiral chute having an open intake end communicating with the said intake opening of the end wall and having an open delivery end communicating with said cone, the open delivery end of the chute located along the cone between the end wall and discharge drum, whereby the cone provides an outwardly tapered surface leading from the open delivery end of the chute to the end of the discharge drum, the portion of the chute adjoining the delivery end having a radius similar to the radius of the cone and providing a regular surface for sliding the material from the surface of the chute to the cone during rotation of the machine, the intake end of the spiral chute forming the leading end thereof during rotation of the machine in discharge direction, whereby the spiral chute elevates the material from the tumbling chamber to said cone, the sloping surface of the cone being effective to feed the material by gravity from the open delivery end laterally toward the discharge drum for advancement through the delivery drum.

6. In a tumbling machine having a tumbling chamber mounted for rotation about its longitudinal axis in charging and discharge directions and having a rearward end wall; means for discharging material from the tumbling chamber by a sliding action comprising, a discharge drum projecting outwardly from said rearward wall along said axis, said drum having a conical surface converging toward the outwardly projected end thereof, a spiral conveyor vane mounted in said drum, a spiral chute mounted externally upon said end wall, the end wall having an intake opening at the periphery of the tumbling chamber to receive the material in the chamber, a cone mounted externally upon the end wall coaxial to the discharge drum and having an end connected to the discharge drum, said cone tapering outwardly from the end wall toward the discharge drum, the said spiral chute having an open intake end communicating with the intake opening of the end wall and having an open delivery end communicating with said cone, the open delivery end of the chute spaced along the cone from the end of the discharge drum, whereby the cone provides an outwardly tapered surface leading from the open delivery end of the chute to the end of the discharge drum the portion of the chute adjoining the delivery end having a radius similar to the radius of the cone and providing a regular surface for sliding the material from the surface of the chute to the cone during rotation of the machine, the intake end of the spiral chute forming the leading end thereof during rotation of the machine in discharge direction, whereby the spiral chute elevates the material from the tumbling chamber to said cone, the surface of the cone being effective to feed the material by gravity from the open delivery end laterally toward the discharge drum for advancement through the discharge drum by said spiral conveyor.

7. A tumbling machine adapted to operate in conjunction with an external separator which separates abrasive fragments and workpieces, the separator including delivery means for advancing the separated abrasive fragments back to the tumbling machine; said tumbling mill comprising, a tumbling chamber mounted for rotation about its longitudinal axis and having a rearward end wall, a discharge drum mounted upon the said rearward end

16

wall concentric with said longitudinal axis and projecting outwardly, a collector chamber surrounding the discharge drum and having an end attached to the rearward end wall, means for advancing abrasive fragments and workpieces from the tumbling chamber to the discharge drum, the outer end of the discharge drum discharging the materials upon said separator, a collector ring mounted upon the outer end of the collector chamber, said ring having a diameter substantially larger than the collector chamber, the collector ring including a wall joined to the end of the collector chamber and having a lip spaced from said wall, thereby to confine the abrasive fragments delivered by the said delivering means of the separator, a series of radial abrasive return chutes mounted upon the wall of the collector ring, said chutes having open outer ends adjacent the periphery of the ring, the chutes having inner ends communicating with openings in the wall of the ring thereby to deliver the abrasive fragments to the collector chamber during rotation of the machine, and means mounted upon the rearward end wall of the tumbling chamber for advancing the abrasive fragments from the collector chamber to the tumbling chamber during rotation of the machine.

8. A tumbling machine adapted to operate in conjunction with an external separator which separates abrasive fragments and workpieces, the separator including delivery means for advancing the separated abrasive fragments back to the tumbling machine; said tumbling mill comprising, a tumbling chamber mounted for rotation about its longitudinal axis and having a rearward end wall, a discharge drum mounted upon the said end wall concentric with said axis and projecting outwardly, a collector chamber surrounding the discharge drum and having an end attached to the rearward end wall, means for advancing abrasive fragments and workpieces from the tumbling chamber to the discharge drum, the outer end of the discharge drum discharging the materials upon said separator, a collector ring mounted upon the outer end of the collector chamber, said ring having a diameter substantially larger than the collector chamber, the collector ring including a wall joined to the end of the collector chamber and having a lip spaced from said wall to confine the abrasive fragments delivered by the delivery means of the separator, conveyor means mounted upon the wall of the collector ring, the conveyor means having outer ends adjacent the periphery of the ring and having inner ends communicating with openings in the wall of the ring, thereby to deliver the abrasive fragments to the collector chamber during rotation of the machine.

9. A tumbling machine adapted to operate in conjunction with an external separator which separates abrasive fragments and workpieces, the separator including delivery means for advancing the separated abrasive fragments back to the tumbling machine; said tumbling mill comprising, a tumbling chamber mounted for rotation about its longitudinal axis and having a rearward end wall, a discharge drum mounted upon the said end wall concentric with said axis and projecting outwardly, a collector chamber surrounding the discharge drum and having an end attached to the rearward end wall, means for advancing abrasive fragments and workpieces from the tumbling chamber to the discharge drum, the outer end of the discharge drum discharging the materials upon said separator, a collector ring mounted upon the outer end of the collector chamber, said ring having a diameter substantially larger than the collector chamber, the collector ring including a wall joined to the end of the collector chamber and having a lip spaced from said wall to confine the abrasive fragments delivered by the delivery means of the separator, a series of radial abrasive return chutes mounted upon the wall of the collector ring, each of said chutes being generally square in cross section and having spaced side walls, the outer ends of the side walls being spaced from the ring to provide intake openings, a baffle mounted intermediate the spaced side walls and having

an outer end joined to the ring to deflect abrasive fragments into the chute, the chutes having inner ends communicating with openings in the wall of the ring to deliver the abrasive fragments to the collector chamber during rotation of the machine.

10. In combination with a tumbling machine having an open charging cone, a power operated loader for elevating and delivering material to the open end of the cone comprising, a vertical guide frame, a carriage mounted relative to the vertical frame, guide means on the carriage connecting the carriage to the frame, a hopper, said hopper including a pair of spaced side walls and a discharge chute at one end, pivot means on the carriage, means on the hopper connected to the said pivot means, a hoist mounted upon the frame for elevating the carriage and hopper, the hoist having a cable extending therefrom, an equalizing member extending transversely across the top of the hopper, said cable connected to the equalizing member intermediate the length thereof, a pair of equalizing cables anchored to the opposite ends of the equalizing member and extending alongside the side walls of the hopper, the lower ends thereof being anchored to the lower portion of the hopper, respective arcuate cable guides mounted upon the said side walls at opposite sides and extending generally at a tangent to the axes of said equalizing cables and loosely confining the same, and stop means on the frame engageable with the carriage at an elevated position thereof to stop the carriage and to rotate the hopper about said pivot means upon continued upward motion of the hopper thereby to deliver the material into the cone.

11. In combination with a tumbling machine having an open charging cone, a power loader for elevating and delivering material to the open end of the charging cone comprising, a vertical guide frame, a carriage, guide members on the carriage connecting the carriage to the guide frame for vertical movement of the carriage relative to the frame, a hopper having a discharge chute at its forward end, pivot means connecting the carriage and hopper, the pivot means located upon an axis extending transversely below the forward end of the hopper, a hoist mounted upon the guide frame for elevating the carriage and hopper, the hoist including a cable connected to the hopper at a plane located rearwardly of the said pivot means, stop means mounted on the frame and engageable with the carriage at an elevated position, a vertical guide flange mounted upon the frame at opposite sides, a guide pin mounted upon the hopper at opposite sides and residing at the lower portion of the guide flanges when the hopper is in lowered position, the pins traversing the vertical flanges during upward motion and maintaining the hopper in horizontal position as the same is elevated, the guide pins disposed above the upper ends of the flanges when the carriage engages the stop at its upper limit of travel, the hoist thereby tilting the hopper about the pivot means to discharge the material into the open cone.

12. In combination with a tumbling machine having an open charging cone, a power loader for elevating and

delivering material to the open end of the charging cone comprising, a vertical frame disposed adjacent the open end of the cone, a carriage, guide members on the carriage connecting the carriage to the frame for vertical carriage movement, a material conveying hopper having a discharge chute at one end projected forwardly toward the end of said cone, pivot means connecting the hopper to the carriage, the pivot means extending transversely of the hopper below the discharge chute, a hoist on the guide frame for elevating the carriage and hopper, the hoist including a cable connected to the hopper at a plane located rearwardly of the said pivot means, and stop means on the frame engageable with the carriage at an elevated position thereof, continued elevation of the hopper by the hoist thereby tilting the rearward portion of the hopper upwardly, the pivot means located at a point to cause the end of the discharge chute to generate an arcuate path about the pivot means toward and through the plane of the open end of the cone to an angular position to discharge the material into the cone.

13. In combination with a tumbling machine having an open charging cone, a power loader for elevating and delivering material to the open end of the charging cone comprising, a vertical frame disposed adjacent the open end of the cone, a carriage, guide members on the carriage connecting the carriage to the frame for vertical carriage movement, a material conveying hopper having a discharge chute at one end projected forwardly toward the end of said cone, pivot means on the carriage, the hopper being pivotally connected to the pivot means, a hoist on the guide frame for elevating the carriage and hopper, the hoist including a cable connected to the hopper at a plane located rearwardly of the said pivot means, a vertical guide rail on the frame, a guide pin on the hopper slidably engaged relative to the rail for vertical movement with the hopper, the guide pin maintaining the hopper in horizontal position during its elevating motion and terminating at a plane below the upper limit of travel of the pin, stop means on the frame engageable with the carriage at an elevated position thereof, continued elevation of the hopper by the hoist thereby tilting the rearward portion of the hopper upwardly, the pivot means located at a point to cause the end of the discharge chute to generate an arcuate path about the pivot means toward and through the plane of the open end of the cone to an angular position to discharge the material into the cone, and a stop mounted on the frame in a position intercepting the arcuate path of motion of the guide pin, thereby to limit the tilting motion of the hopper.
